MICHAEL M. BOHEN, OF CASPER, WYOMING.

SHOVELING-MACHINE.

1,353,142.

Specification of Letters Patent. Patented Sept. 21, 1920.

Application filed July 14, 1919. Serial No. 310,632.

To all whom it may concern:

Be it known that I, MICHAEL M. BOHEN, a citizen of the United States of America, residing at Casper, county of Natrona and State of Wyoming, have invented a new and useful Shoveling-Machine, of which the following is a specification.

This invention relates to improvements in shoveling machines.

- 10 The objects of the invention are: to provide a machine which is adapted, primarily, for removing the muck in tunnel excavation work, but which is also adapted for other kinds of shoveling work such as in the excavation of streets and roadways. Further, to provide a shoveling machine, comprising a wheeled frame having a power-operated endless carrier, a rotary shoveling device for shoveling material to the conveyer, and 15 coöperating rotary shoveling devices for shoveling material into the path of the first-mentioned shoveling device, whereby a continuous supply of material is supplied to the endless carrier, means being provided for automatically moving the machines forward as the material is cleared away. Further, to provide a shoveling machine in which the shoveling elements can be raised out of operative position when it is desired to move the machine without performing the shoveling operation. These objects are accomplished by the mechanism illustrated in the accompanying drawings, in which:
- 20 Figure 1, is a side elevation of the improved shoveling machine, the same being mounted on tracks.
- 25 Figure 2, is a plan view of the same.
- 30 Figure 3, is a front end elevation thereof.
- 35 Figure 4, is a plan view of the rear portion of the truck showing the mechanism carried thereby for moving the machine forward, and for effecting the operation of the conveyer and of the shoveling elements.
- 40 Figure 5, is a sectional view on the line 5—5 of Fig. 4.
- 45 Figure 6, is a fragmental sectional view illustrating the manner of raising the forward end of the machine above the ground.
- 50 Figure 7, is a fragmental sectional view on the line 7—7 of Fig. 2 and Fig. 8 is a side view of a portion of one of the shovel arms.
- 55 Referring to the accompanying drawings: The numeral 1 designates a truck which supports the operating mechanism of the machine, and which comprises side members 2, which are preferably channel-irons,

connected by cross bar 3, the side members 2, being mounted on wheels 4, the axles of which are rotatably journaled in suitable bearings on the under edges of the side members. The axles are provided, on one side of the truck, with sprocket wheels 5, which are connected by a chain 6. The truck carries its own motor, which may be either of the air or electric type, as conditions may make necessary, the motor forming no part of the present invention. As illustrated, however, an electric motor 7, of a common type, is employed, and this motor is mounted on intermediate cross bar 3, adjacent to the rear axle. The motor shaft has a pinion 8, in mesh with a gear wheel 9, on a shaft 10, which is supported at one end in bearings on a standard 11 secured upon the adjacent side frame 2; and at its other end in bearings on a standard 12 secured upon the same intermediate cross bars which support the motor. A second shaft 13, is mounted in bearings on the standards 11 and 12 and is provided with a gear wheel 14, in mesh with a gear wheel 15, on the shaft 10, by which power from the motor is transmitted to the shaft 13. The end of the shaft 13, adjacent the gear wheel 14, is provided with a sprocket wheel 16, and the opposite end of the shaft 10, from the gear wheel 15, is provided with a sprocket wheel 17, the function of these wheels being hereinafter set forth. The rear axle of the truck has rigidly secured thereon, a ratchet wheel 18, which is engaged by a pawl 19, on a lever 20, the lower end of which is pivotally mounted on the said axle. The upper end of the lever 20 is pivotally attached to one end of a connecting rod 21, the opposite end of which connects with an eccentric 22, mounted on the shaft 13. By reference to Figs. 4 and 5, it will be seen that the eccentric reciprocates the rod 21, which oscillates the lever 20, whose pawl 19 engages and intermittently rotates the ratchet wheel 18, by which the rear axle is rotated, and this rotation is transmitted to the forward axle by the chain 6, whereby the truck is propelled forward. A pair of parallel conveyer-supporting bars 23, are supported upon the truck and these bars are inclined upward from the front end of the machine to the rear end thereof, and are supported in the following manner:

105 Upright bars 24, are bolted at their lower ends, to the rear ends of the side members 2,

of the truck, and their upper ends are bolted to the rear ends of inclined bars, as shown in Fig. 1, and thus support the rear ends of the said bars 23. Uprights 25 are also bolted to the side members of the truck and to the inclined bars, and support the latter bars intermediate of their ends; and the forward portions of the inclined bars are secured to a cross bar 26, the ends of which are bolted to side plates 27, which are connected to the side members of the truck by bars 28. The forward ends of the side plates 27, are provided with rollers 29, which rest on the ground and thus coöperate with the bars 28 in supporting the forward ends of the inclined bars. To the forward ends of the plates 27 are also secured the lower ends of spaced bars 30 and 31, which are arcs of a circle whose center is the axis 20 of the shaft 13, and the upper ends of these bars are bolted to the forward ends of horizontal side bars 32, the opposite ends of which are bolted to the uprights 24, and intermediate of the ends, the bars 32 are bolted to the inclined bars 23 and also to the upper ends of the uprights 25, as shown by Fig. 1. Each bar 30 is preferably an angle bar, and each bar 31 is preferably a T bar, and the T bars 31, are connected at 30 their upper ends by a cross bar 33. The bars 30 and 31, on each side of the machine, form slideways for bearing boxes 34, to be hereinafter described. Spaced from each angle bar 30, is a T bar 35, which with the angle bars 30, form slideways for bearing boxes 36, which are in axial alinement while the axes of the boxes 34 are parallel and at right angles to those of the boxes 36. The boxes 34 are formed with reduced portions 37, 40 which fit in between the opposing edges of the bars 30 and 31, and the boxes 36 also have reduced portions which fit in between the opposing edges of the bars 30 and 35, and each box 34 is rigidly connected to the 45 adjacent box 36 by an angle plate 38, the wings of which are bolted respectively to the two bearing boxes, each wing overlapping the opposing edges of one of the slideways so that each box is thereby held in its slide-way. The upper ends of the T bars 35 are connected by a cross bar 35A, and the bars 35A and 33 are connected by tie plates 35B. Each box 36 is also connected to a box 39 by an angle plate 40, similar to the angle plate 38, and each box 39 is in axial line with the adjacent box 34, as will be understood by reference to Fig. 2. It will thus be seen that the boxes 34 and 39 are connected to the box 36 on each side of the machine 55 and, therefore, when the boxes 36 are raised they raise the boxes 34 and 39 with them. A shaft 41 is mounted in the boxes 36 and has mounted on each end a bevel gear 42, and a sprocket wheel 43 is also mounted on this 60 shaft, which is connected by a sprocket chain

44, with the sprocket wheel 16 on the shaft 13. A rotary shovel is centrally mounted on the shaft 41, and this shovel comprises a hub 45, having radial arms 46, each of which is made up of two sections connected by a hinge joint 47, which permits the outer section to swing on the inner section in a counter direction only to its rotary movement, but the outer section is normally held against swinging movement by a spring 48, 70 having a central coil which surrounds the pivot bolt of the hinge, the end portions of the spring, which are under tension, bearing against the respective sections of the arm, as shown by Fig. 8. The outer end of 75 each arm has a suitable shovel 49 bolted thereon, and these shovels are adapted to deliver material to an endless conveyer 50, which is mounted on drums 51, supported on shafts 52, which are journaled in bearings 53, secured on opposite ends of the inclined bars 23; the conveyer comprising a belt having suitable transversely arranged buckets 54. The upper shaft 52, of the conveyer, has a sprocket wheel 55, on one end, 80 which is connected by a sprocket chain 56, with the sprocket wheel 17, on the power driven shaft 10. A shaft 57 is mounted in the axially-aligned bearing boxes 34 and 39 on each side of the machine, and these shafts 85 are provided with bevel gears 58, which mesh with the bevel gears 42 on the shaft 41. The outer ends of these shafts are provided with rotary elements in the nature of picks, each of which comprises a hub 59, 90 and radial arms 60, which are identical in construction with the arms 46, of the rotary shovel, each arm comprising two sections having a hinge connection 61, and springs 62, for normally holding the outer sections 95 against swinging movement. The outer ends of the arms 60 are provided with suitable picks 63, which are adapted to move material into the path of the rotary shovel which catches the said material and throws 100 it on to the conveyer. The rotary shovel, without the coöperation of the rotary picks would only clear a path of limited width, but with the coöperation of the picks not only a much wider path is cleared, but loose 110 material is continuously thrown into the path of the shovels, which are thus kept supplied. The springs 48 and 62 prevent the outer sections of the respective arms 46 and 60 from rocking on their hinges, under ordinary resistance, but when either the shovels or picks encounter more than ordinary resistance, or resistance sufficient to bend or break the arms if they were made of a single section, the springs permit the outer sections 120 to swing back and escape the obstructions causing the excess resistance, thus preventing injury to the arms. 125

From the foregoing description, it will be seen that power, from the power-driven 130

shaft 13, is transmitted to the shaft 41 of the rotary shovel, through the medium of the sprocket chain 44, which connects the sprocket wheels 16, on the shaft 13, with the sprocket wheel 43, on the shaft 41, thereby rotating the shaft with its shovels; and the bevel gears 42, on the end of the shaft 41, meshing with the gears 58, on the shafts 57 rotate the said shafts with their picks, the conveyer being driven to chain 56, which connects the sprocket wheel 17, on the power shaft 10, with the sprocket wheel 55, on the upper conveyer shaft 52. When it is desired to propel the machine, without utilizing the shoveling mechanism, the said mechanism is raised out of operative position in the following manner: To each bearing box 36, is secured the lower end of a chain, or other flexible connection 64, the upper ends of which are connected to the forward end of a lever 65, which is mounted on a shaft 66, which is supported in bearings 67, secured upon the side bars 32. The handle end of this lever is bent to lie adjacent to one of the side bars 32 so as to be in easy reach of an attendant, and when the handle end of the lever is pressed down, the chains 64 are drawn upon, and the shoveling elements are raised out of operative position and are held by the engagement of the lever with a toothed rack 68, which is secured to the adjacent side bar 32. It is sometimes necessary to raise the front end of the machine above the ground, and this is accomplished in the following manner: The front axle of the truck is supported in bearings 69, which rest against the under edges of the side frames 2, of the truck, but are not bolted thereto. Each of these bearings is bolted to the ends of a U-bolt 70, as shown in Fig. 6, which extends loosely through bolt holes in the flange portion 2A of the side frame 2. Upon the axle 4A adjoining the side frames, are pivotally mounted the lower ends of levers 71, and the lower end portions of these levers are formed with cams 72, which engage rollers 73, on the side frames 2. When the levers 71 are moved in the direction of the arrow, Fig. 6, the cams 72 engage the rollers 73, and thereby lift the front end of the truck, the side frames 2, sliding on the U-bolts, which are secured to the bearings 69, which support the axle 4A. Thus the front end 55 of the truck together with the shoveling elements is raised, while the front truck wheels remain upon the tracks.

Having described my invention, what I claim as new, and desire to secure by Letters 60 Patent is:

1. In a shoveling machine of the character described, the combination with a truck having a motor thereon, of an inclined frame supported on said truck, an endless conveyer mounted on said inclined

frame and operated by said motor, upright frames adjacent the forward end of the conveyer, a rotatable shoveling device slidably mounted in the upright frames, and operated by the motor, for delivering material to the conveyer, rotatable means on each side of the shoveling means for supplying material to the said shoveling means, and operated thereby, said latter means turning in paths at right angles to that of the shoveling means, and being connected with the shoveling means to be raised or lowered therewith, and means for raising or lowering the same and a pawl and ratchet mechanism connected operated by the motor, for moving the truck forward.

2. In a shoveling machine, the combination with a truck having a motor thereon, of a frame supported on the truck having opposite pairs of upright slideways on its forward end, the slideways of each pair facing at right angles to each other, transversely alined bearing boxes mounted in correspondingly facing slideways of the opposite pairs of slideways, a shaft mounted in said boxes, having a bevel gear on each end, a pair of longitudinally alined bearing boxes on each side of the machine, each pair being rigidly connected with the adjacent box of the transversely alined pair, a shaft in each pair of longitudinally alined boxes, said shafts having bevel gears in mesh with the gears on the transverse shaft, one bearing box of each pair of longitudinally alined boxes being mounted in the remaining slideway of the adjacent pair of slideways, rotatable shoveling means on all of said shafts, power transmitting means connecting the motor and the said transverse shaft, an endless conveyer supported on the truck and operated by the motor, and adapted to receive material from the shoveling means, a pawl and ratchet mechanism operated by the motor and connected with one of the truck axles for moving the truck forward, and means for raising the shoveling mechanism out of operative position.

3. In a shoveling machine, a truck having a motor thereon, an endless conveyer supported on the truck and operated by the motor, a rotary shovel comprising a transverse shaft and power transmitting means connecting the same with the motor, a hub on said shaft having radial arms, and shovels on the outer ends of said arms for delivering material to the conveyer; gears on the ends of said shaft, side shafts at right angles to the transverse shaft, having gears in mesh with the gears on the transverse shaft, hubs on said shafts having radial arms, and members on the outer ends of said arms for delivering material to the rotary shovel, slidable bearing boxes for all of said shafts, means rigidly connecting the boxes of each side shaft with the adja-

cent box of the transverse shaft, upright slideways for the boxes of the transverse shaft, and for one box of each side shaft, a lever supported on the truck and chains connecting one end of the same with the boxes on the transverse shaft, thereby to raise the said shoveling mechanisms out of operative position, and means operated by the motor and connected with one of the 10 truck axles for intermittently moving said truck forward.

4. In a shoveling machine, the combination with an endless conveyer and means for operating the same, of rotatable shoveling 15 means operated by the conveyer operating means, for supplying said conveyer, comprising a transverse shaft, slidable bearings therefor, upright slideways for said bearings, and means for raising said shaft and 20 its bearings in said slideways, a hub on the shaft having radial arms, each comprising two sections connected by a hinge, springs for holding the outer sections under a yielding tension, and shovel elements on the ends 25 of the outer sections, side shafts at right angles to the transverse shaft, each of which has bearings rigidly connected with the adjacent bearing of the transverse shaft, and upright slideways for said bearings, gear- 30 ing connecting the ends of the transverse shaft with the side shafts, hubs on said shafts having radial arms comprising two sections connected by a hinge, and springs for holding the outer sections under yield- 35 ing tension, said outer sections having picks for supplying material to the shovel elements, a pawl and ratchet mechanism connected with one of the truck axles, and means operated by the conveyer operating 40 means for actuating the said pawl.

5. In a shoveling machine, the combination with a truck, a motor thereon, and an endless conveyer operated by said motor of oppositely arranged upright slideways ad- 45 jacent the forward end of said conveyer, bearings in said slideway, a transverse shaft mounted in said bearings having radially disposed shovel members thereon, ar- ranged to supply the said conveyer, and a 50 chain and sprocket connection between said shaft and motor, slidable bearings connected to the first mentioned bearings having side shafts mounted therein at right angles to the transverse shaft and having radially 55 disposed shovel members arranged to supply the first mentioned shovel members, gearing connecting the ends of the transverse shaft and the side shafts, an upright slideway for a bearing of each of the side shafts, means 60 for operating all of said shafts, means for raising said shovel members out of operative position, and a pawl and ratchet mechanism operated by the motor, for intermittently moving said truck.

6. In a shoveling machine, a truck, hav-

ing a motor thereon, drums supported on said truck, an endless conveyer supported on the drums, gearing and a chain and sprocket connection between said motor and one of said drums, a transverse shaft, rotatable 70 shovels thereon for supplying said conveyer, a motor-driven shaft, a sprocket and chain connection between said motor driven shaft and said transverse shaft, shafts on opposite sides of the machine and gearing connecting 75 them with the ends of the transverse shaft, rotatable shovels on the side shafts for sup- 80 plying material to the rotatable shovels on the transverse shaft, rigidly connected bearings for each side shaft and the adjacent bearing of the transverse shaft, upright slideways for said bearings, means for rais- 85 ing said bearings in unison to lift the shovels out of operative position, and means for lim- iting the downward movement of said bear- 90 ings.

7. In a shoveling machine, the combina- 95 tion with a truck, an endless conveyer there- on, a motor carried by the truck for operat- 100 ing said conveyer, and rotatable shovel means operated by said motor for supplying material to said conveyer, of means for rais- 105 ing the forward end of said truck frame away from the forward axle, comprising levers mounted on the said axle, having cam portions theron, rollers on the truck frame which are engaged by said cam portions when the levers are swung in one direction, and guides secured upon said axle for steadyng the movement of the truck frame 110 when raised and lowered.

8. In a shoveling machine, the combina- 115 tion with a truck, an endless conveyer there- on, a motor on said truck, a chain and sprocket connection between said motor and the endless conveyer, a rotary shovel for sup- 120 plying material to the conveyer, rotary side shovels, gearing connecting them with the first mentioned shovel, and gearing and a chain and sprocket connection between the said motor and the first mentioned shovel, of means for moving said truck for- 125 ward, comprising a ratchet wheel rigidly secured on one of the truck axles, a lever pivotally mounted on said axle having a pawl to engage said ratchet wheel, an eccen- tric operated by said motor, and a rod connected at one end to said eccentric and at its other end to the pawl carrying lever.

9. In a shoveling machine, a truck having 120 a motor thereon, a frame supported on said truck, an endless conveyer on said frame and a chain and sprocket connection be- 125 tween the motor and the conveyer, a trans- verse shaft having rotary shovels for sup- plying material to the conveyer, bearings for said shaft and upright slideways for said bearings, a shaft and gearing connecting the same with the motor shaft, a chain and sprocket connection between the motor 130

driven shaft and the transverse shovel carrying shaft, said slideways being arcs whose center is the axis of the said motor driven shaft, shafts at right angles to the trans-
5 verse shaft, having rotary shovel elements for supplying material to the first mentioned shovels, bearings for the latter shafts, and slideways for said bearings having the same curvature as the first mentioned slide-
10 ways, the bearings on each side of the machine being rigidly connected, a lever sup-
ported on said truck and a chain connected therewith, and with the transverse shaft bearings, for raising and lowering said bearings, and a rack for engaging said lever. 15

In testimony whereof I affix my signature in presence of two witnesses.

MICHAEL M. BOHEN.
